UNITED STATES PATENT OFFICE.

PAUL CHARLES LEMALE, OF PARIS, FRANCE.

CONDENSING PUMP.

Application filed May 28, 1923, Serial No. 642,017, and in France June 30, 1923.

The invention relates to vapour, especially steam, condensers or compressors and its object is to provide a new method and means for condensing or compressing vapor offering numerous advantages over systems of condensation known heretofore.

The novel new method has for its objects to reduce loss of energy, to obtain rapid condensation where employed for that purpose, and to regenerate steam for heating where employed for steam-compressing purposes.

The invention relates to plants of the kind hitherto employed for condensing steam which comprise a condensing pump with a rotary ejector for injecting water into the mixing chamber which is supplied with the steam to be condensed.

The new method primarily consists in giving the ejected jets of liquid, after they have entrained vapour from the mixing chamber, a free path while gradually changing their kinetic into pressure energy.

To obtain efficiency, in a steam condensing plant for example, I divide the water to be discharged from the ejector into a plurality of jets distributed over its periphery in such manner that the whole surface of each and every jet is presented to the steam, so entraining, cooling and condensing it, and after this entrainment, I allow the jets a free path between annular smooth surfaces to a guide chamber to the discharge outlet, the pressure of the water being so raised from vacuum pressure to atmospheric pressure or more.

The impeller projects the jets of water directly into the mixing chamber, without the aid of any distributor, by giving to them kinetic energy only, without application of pressure, which feature excludes all loss by subsequent retransformation of energy.

After having passed through the mixing chamber, where the condensation of steam takes place, the water-jets, carrying along with them the condensed steam, pass between two smooth plates with parallel faces.

Moreover, a double row of water-jets in staggered relation, traverse the free space between the two plates without contact with the latter to any considerable extent, owing to the fact that the faces of the plates are parallel with their direction. In this manner a complete transformation of kinetic energy into potential energy is obtained

owing to the gradual reduction in speed of the ejected water.

Known pumps of the kind described first subject the injection water to pressure, which water is thereafter distributed, either by means of a distributor with tray-like members of thin disc-form, or by means of nozzles disposed on the periphery of the rotary ejector, which effect atomization of the water. In both these cases there is double transformation, and hence loss of energy.

An example of apparatus for carrying out the invention is represented in the accompanying drawings wherein:

Figure 1 is a sectional elevation of the apparatus, taken on the line X—X in Figure 2,

Figure 2 is a sectional elevation taken on the lines Y—Y in Figure 1,

Figure 3 a section, on a larger scale, of a fragment of the pump wheel taken on the line O—O in Figure 4, and illustrating the mode of construction of the said wheel, and

Figure 4 is a plan view of the said fragment, showing the outlets of the water jets, the staggered arrangement of said outlets and the mode of constructing the wheel;

Figure 5 is a detail elevation of one of the block covers,

Figure 6 is a detail vertical sectional view of the same on the plane indicated by the line X₁—X₁ of Figure 5.

The body of the apparatus is composed of two half-envelopes of metal, assembled according to a diametrical plan W. The aspiration conduit for the injection water B, is divided into two branches B², B² which lead into an aspiration chamber D⁴ of the impeller; this chamber is constituted by the block cover D¹ which comprises a prolongation made in the foundry, forming an interior chamber, provided with an opening D⁵ which coincides, making a stanch joint with the opening of the conduit B². The alimentation water drawn through the impeller goes into the conduits B² and then into the aspiration chamber D⁴ in order to enter finally into the impeller.

In Figure 1 the admission of the steam to be condensed is at A, the injection water admission at B, and their respective paths are shown by arrows, the broken line arrows indicating steam and the full line arrows water.

The pump wheel C, which is keyed on the

driven shaft D, draws in injection water through the inlets B¹, and, by the wheel's rotation, imparts kinetic energy to this water, the latter being injected in two circular rows of jets in staggered relation from the periphery of the wheel.

At a certain distance from, and concentrically with, the pump wheel, are fitted two circular ejector plates K the inner faces 10 of which are smooth, and are arranged parallel to the direction of the water-jets.

The water-jets which issue from the openings J of the pump wheel, traverse the annular space F which is provided between the periphery of the pump wheel C and the inlet to the smooth plates K. This space F is called the "mixing chamber". In fact, whilst traversing the space F, the water-jets produce a vacuum, entrain the steam which enters through A, and condense this steam by contact therewith. The water-jets in annular rows then pass between the smooth and parallel plates K, and transform their kinetic energy into pressure energy, 20 owing to the gradual reduction of speed of the water whilst moving more or less circumferentially between the plates.

It should be noted that the distance between the two smooth plates K is greater 30 than the width of the two rows of water-jets and that the surface of the two smooth plates K is parallel to the direction of the jets. These conditions are indispensable for the design of an exclusively kinetic apparatus.

On leaving the ejector plates K, the condensing water and the condensed steam discharge into a header S, which leads to the opening T through which air and water 40 are discharged from the pump.

The pump wheel C comprises a central disc C¹ (Figure 4) and two outer walls C² the latter being integral with main vanes C³ and intermediate vanes C⁴.

These three parts of the pump wheel are assembled by screws H traversing the thickness of the main vanes, the threaded part of these screws being screwed into the central disc C¹.

A novelty in the pump wheel resides in 50 the alternation of the openings J for the jets

at each side of the central disc C¹. This is obtained by displacing one plate C² with respect to the other a circumferential distance equal to half the pitch of the vanes. 55 The effect of staggering the openings J will be that each jet ejected by the rotation of the pump wheel C will present its entire surface to the steam to be condensed and produce rapid and economical condensation. 60

It will be seen that this mode of water ejection utilizes moving water for condensing steam to produce a vacuum, and for raising in pressure the condensed water and the extracted air from the pressure of the 65 vacuum produced to atmospheric pressure.

I claim:—

1. A vapour condensing or compressing device of the kind described, comprising in combination a mixing chamber having an inlet for vapour, a suction chamber having an inlet for liquid, a rotary impeller journalled in the latter chamber and having a plurality of jet-forming passages connecting the two chambers a pair of stationary parallel annular plates spaced radially from the impeller periphery and spaced apart a distance somewhat greater than the width of the outlets of the jet-forming passages and a circumferential guide chamber embracing 70 the outer ends of said plates and having a tangential discharge outlet. 75

2. A vapour condensing or compressing device according to claim 1, wherein the impeller has jet-forming passages having outlets in staggered relation. 85

3. A vapour condensing or compressing device according to claim 1, wherein the impeller comprises an inner disc and two outer discs the latter each having jet-forming 90 passages. 95

4. A vapour condensing or compressing device according to claim 1, wherein the impeller comprises an inner disc and two outer discs, the latter each having jet-forming passages and being angularly displaced from each other an amount equal to the angular pitch of the outlets of the jet-forming passages in each disc.

In witness whereof I affix my signature.

PAUL CHARLES LEMALE.
